DRAWBENCH

Edwin J. McIlvried, Akron, and Norman H. Nye, Cuyahoga Falls, Ohio, assignors to The Vaughn Machinery Company, Cuyahoga Falls, Ohio, a corporation of Ohio.

Application December 20, 1943, Serial No. 514,936

14 Claims. (Cl. 205—7)

1 The present improvements, relating as indicated to draw-benches, have more particular regard to the loading mechanism whereby work-pieces may be successively supplied to such bench. While herein illustrated and described in connection with a draw-bench designed for drawing tubes, it will be understood that the present improved loading mechanism may also be advantageously employed in connection with draw-benches for drawing rods, bars, or other work-pieces of solid cross-section.

In drawing tubes and the like, the work-pieces are frequently of considerable length and the handling thereof preliminary to their introduction into the die of the drawing machine proper constitutes no small problem. Thus in order to draw a tube, after reducing or pinching the one end to which the drawing mechanism, usually in the form of a carriage provided with gripper jaws, is attached, a mandrel requires to be supported within the tube adjacent such pinched end; this mandrel of course being attached to a holding rod of greater length than the tube which is to be drawn. Accordingly the open end of the latter requires to be placed over the mandrel and the tube then moved longitudinally until its pinched end is brought in proper relation to the mandrel, whereupon the pinched end of the tube with the mandrel therein requires to be inserted in the die so that such pinched end of the tube may be gripped by the drawing device.

One principal object of the present invention is to provide a loading mechanism of simple construction in which, if desired, tubes of considerable length may be handled preparatory to a drawing operation such as just described, i. e. in which such a tube may be moved longitudinally in one direction over the mandrel and its supporting rod and then moved together with the mandrel in a reverse direction to project the pinched end of the tube through the die in position to be gripped by the drawing device. A further object is to provide a loading mechanism in which the first of the operations just described may be performed on one tube simultaneously with the drawing of another previously placed or loaded tube. Still another object is to eliminate the use of elongate tubular members to receive and guide the tube while being placed over the mandrel. The invention also comprises improved means for supplying lubricant within a tube during the drawing operation so as to reduce the friction between the tube and mandrel at the point of draw.

To the accomplishment of the foregoing and

related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

- 10 10 In said annexed drawings:
Fig. 1 is a top plan view of a loading mechanism embodying our present improvements;
Fig. 2 is a side elevation thereof;
Fig. 3 is a transverse section on a somewhat larger scale, the plane of the section being indicated by the line 3—3, Fig. 2;
Fig. 4 is a broken side elevation of a detail found at the right hand end of the mechanism as shown in Figs. 1 and 2;
20 Fig. 5 is an end elevation of the same detail viewed in the direction indicated by the section line 5—5, Fig. 2;
Fig. 6 is a view similar to Fig. 4 showing in side elevation an adjacent detailed part of the mechanism;
25 Fig. 7 is an end view of such detail as viewed from the right (see section line 7—7, Fig. 6);
Fig. 8 is a top plan view on a larger scale of the left hand portion of the mechanism as shown in Fig. 1;
30 Fig. 9 is a central vertical section of such portion of the mechanism as indicated by the line 9—9, Fig. 8;
Fig. 10 is a transverse section of a detail, the plane of the section being indicated by the line 10—10, Fig. 8;
35 Fig. 11 is an end view of one of the work-piece holders comprising the mechanism as viewed from the left in Fig. 9 (see line 11—11);
40 Fig. 12 is a sectional view of such work-piece holder, the plane of the section being indicated by the line 12—12, Fig. 11;
Fig. 13 is a sectional view of a portion of the actuator for such work-piece holder, the plane 45 of the section being indicated by the line 13—13, Fig. 9;
Fig. 14 is a vertical sectional view on the plane indicated by the line 14—14, Fig. 9;
Fig. 15 is a similar view as indicated by the line 15—15, Fig. 9;
50 Fig. 16 is an end view of the portion of the mechanism in question as viewed from the left in Figs. 8 and 9;
Fig. 17 is a vertical axial view of certain of the 55 parts shown in transverse section in Fig. 14;

Fig. 18 is a transverse sectional view, the plane of the section being indicated by the line 18—18, Fig. 17;

Fig. 19 is partly a plan and partly a sectional view, more or less diagrammatic in character, showing more particularly the connections for supplying lubricant to the work-holders illustrated in Figs. 8 and 9;

Fig. 20 is a vertical longitudinal section corresponding to that of Fig. 9 but showing the opposite end of the loading mechanism, i. e. the right hand end of Figs. 1 and 2;

Fig. 21 is a transverse section taken on the plane indicated by the line 21—21, Fig. 20; and

Fig. 22 is a central sectional view of one of the work-piece holders showing the manner in which the mandrel rod is attached.

The draw-bench with which our improved loading mechanism is designed to be associated forms no part of the present invention and may be of any well known design. The parts of a typical draw-bench wherewith such loading mechanism will be associated when in use are illustrated in Fig. 20 and will be described later in setting forth the operation of the loading mechanism.

Such loading mechanism, as generally illustrated in Figs. 1 and 2, comprises a longitudinally extending main frame 1, conveniently assembled of parallel channel or L-shaped sections as illustrated in Fig. 3, such main frame being supported on bases 2 and 3 at its respective ends and by such number of intermediate pedestals 4 as may be required, depending upon the length of the machine. As previously indicated, for the purpose of handling certain types of tubular products a very long drawing bench may be employed, and a loading mechanism of corresponding length will accordingly be required. The work-pieces, whether tubular or solid, i. e. of rod-like form, are designed to be successively supplied to the machine from the right as viewed in Figs. 1 and 2 and after being loaded therein are then designed to be moved in reverse direction, i. e. to the right, to bring the end of such work-piece in operative relation to the drawing mechanism proper.

Mounted for rotative movement above the main frame or bed 1 is the work-piece carrier which extends substantially the entire length of such bed and is adapted thus to receive the successive work-pieces and deliver them to the draw-bench. The main element of this carrier is a central shaft 5 which in case the over-all length of the machine should make it necessary or convenient will be made up of aligned sections non-rotatively joined together by one or more couplings 6. For the purpose of rotatably supporting shaft 5 on the bed, there is secured to such shaft at spaced intervals a plurality of arcuate bearing rings 7 (see Fig. 3) each of which rests on a pair of trunnion bearings 8, 8, that are attached to and lie a suitable distance above the side walls of the frame to permit such bearing ring to clear the latter. While shaft 5 has been referred to as a rotatable shaft, it will actually require only to be oscillated through an arc of approximately 180° and the openings in the rings, all of which face in the same direction, will at no time drop below the contiguous bearing 8. The number of bearing rings 7 and their spacing along the shaft 5 will of course depend first upon the length of such shaft and secondly upon the character of the work-pieces to be handled, whether large or small, light or heavy.

For the purpose of guiding the work-pieces into and out of the carrier and for assisting in

holding the same in proper place therein, a series of paired guide members 10 is provided, the detailed construction of which is best shown in Figs. 20 and 21. As there shown, each such pair of guide members is secured to the shaft 5 by oppositely extending arms 11 whereby said members are held in alignment longitudinally of and parallel with the shaft. Said guide members furthermore all lie within the space defined by the bearing rings 7. While the guide members may take on various forms, they preferably are of flaring or bell-mouth shape with their larger openings directed toward the right as viewed in Figs. 1 and 2; moreover, they are desirably made openable on the side corresponding with the opening in said bearing rings. To this end, in the specific construction illustrated, each such guide member is split longitudinally, the one section being hingedly connected to the other and suitable securing means, such as the swinging bolt 12, being provided to retain the members closed when in use.

At the left hand end of the machine, as illustrated in Figs. 1 and 2 (see also Figs. 8 and 9), i. e. the end furthest removed from the draw-bench, the corresponding end of carrier shaft 5 is received and additionally supported in a bearing 15 provided in a housing 16 that extends upwardly from the adjacent base 2 of the machine. To such shaft end, beyond bearing 15, is secured a gear 17 which meshes with a vertical reciprocable rack 18, the latter being connected at its lower end with rod 19 of a hydraulic cylinder and piston 20. Through its connection with gear 17 such reciprocating movement of the rack is designed to oscillate shaft 5 through an arc of approximately 180°, first in one direction, then the other.

The supply of liquid or other pressure fluid to cylinder 20 is controlled by a suitable valve, not shown. However, there is shown an electric switch 24, which controls the relay circuit through which such pressure fluid supply is in turn controlled. A horizontally extending rod 21 above bed 2 (see Fig. 9) is operatively connected at one end with such electric switch 24, while its other end is disposed for engagement with the work-piece reciprocating device which will be presently described. A spring 22 associated with rod 21 serves normally to hold the switch 24 in open position so that rack 18 cannot be moved from one to the other of its limiting positions until the rod 21 is moved against such spring to close the switch.

Spaced inwardly (i. e. to the right as viewed in Figs. 8 and 9) a short distance from housing 16, there is non-rotatably secured to shaft 5 a shell 25 that is formed with two oppositely facing guideways 26. The length of these guideways will be somewhat greater than that of the movement which it is required should be imparted to a work-piece in the carrier to move the same into position to be drawn after such work-piece has been loaded in the carrier and the latter oscillated or indexed to align the further end of such work-piece with the draw-bench die.

Reciprocably mounted on each such guideway 26 is a slide 27 provided with a radial projection 28 wherein is longitudinally adjustably mounted a holder 29 for the work-piece and for the mandrel rod 30 where as in drawing a tubular article a mandrel will require to be employed. In order to thus adjustably support holders 29, each is attached to a shaft 31 which is tubular, for a purpose presently to be explained, and which is mounted in the corresponding projection 28 in threaded engagement with a rotatable bushing

32. The latter carries a small gear 33 that meshes with a second gear 34 non-rotatably but slidably mounted on a shaft 35 which extends longitudinally of the machine in parallel relation with main shaft 5 to a point adjacent the further end of the latter, i. e. adjacent the draw-bench. For the purpose of intermediately supporting these holder operating shafts, suitable bearings are provided in radially projecting arms 36 secured at spaced intervals to said main shaft (see Figs. 1, 2 and 3). A key 37 which engages with a keyway in each of the tubular work holder supports 31 holds the latter against rotation so that upon rotating shaft 35 in one direction or the other and thus correspondingly rotating the threaded sleeve 32, said support, and thus the work holder 29, will be longitudinally advanced or retracted.

Projection 28 on each of the slides 27 in which the corresponding work holder support 29 is thus adjustably mounted is further provided with a transverse arcuate rig 38 which is adapted in one rotative position of the slide about the axis of main shaft 5, i. e. when located directly below said shaft, to engage with a transversely notched member 39, carried by a reciprocable slide 39a. The latter (see Figs. 9, 13 and 15) is thus reciprocably mounted on a slide-way 40 that is disposed in parallel relation to shaft 5 on the upper face of bed 2. Member 39 is in the form of an oppositely bevelled head on a plunger 39b that is spring supported in said slide 39a. For the purpose of reciprocating member 39, a hydraulically operated cylinder and piston 41 is provided adjacent cylinder and piston 20, but horizontally disposed, being connected with member 39 by piston rod 42. As shown in Fig. 9, such piston rod is extended, and member 39, together with the work holder support in engagement therewith, has been advanced to its limiting position toward the right, i. e. in the direction of the draw-bench. Upon actuating the cylinder and piston 41 to retract piston rod 42, the parts in question will be moved to the left so as to occupy a position corresponding with that occupied by the corresponding parts of the other work holder as shown in the upper central portion of said figure.

Slide 39a in which member 39 is carried is also provided with a downwardly depending lug 39c which is aligned with the end of rod 21 whereby the relay circuit of piston and cylinder 20 is normally held open, as previously described. Upon retraction of piston rod 42 said lug 39c will engage the end of rod 21 to close such relay circuit and thus render it possible for the operator to actuate piston and cylinder 20 to oscillate the carrier. However, such actuation it will be seen is only possible when the work holder connected through member 39 with said piston rod 42 is thus retracted.

Fixedly secured to the shaft 5 adjacent the inner face of housing 16 are two oppositely directed arms 45, 45 of the form clearly shown in Fig. 14. These arms are disposed so that as the shaft and work carrier as a whole is oscillated first in one and then the opposite direction the curved contacting faces of the arms will engage with a stop 46 that projects inwardly from said housing 16. This stop preferably consists of a heavy rubber ring mounted on a pin 46 so that the impact of the rotating carrier will be resiliently taken up.

Also mounted on shaft 5 adjacent the stop 75 Fig. 19 (see also Fig. 20) where the upper man-

mechanism just described is a valve mechanism 50 (see Figs. 17 and 18) which controls the supply of lubricant to the bore 61 of the tubular shaft 31, whereby the work holders 29 are supported. The lubricant in question, whether of oil or other composition, is a liquid and is brought to the valve mechanism 50 through a central passage 52 that extends inwardly from the outer end of shaft 5, an external supply line 53 being connected with such passage by means of a suitable coupling 54. At a point adjacent the valve mechanism two oppositely directed radial passages 55, 55 extend from passage 52 to the exterior of shaft 5 and the housing of the valve mechanism is formed with chambers 56, only one being fully shown in Fig. 18, that communicate with said radial passages respectively. Each of these chambers are in turn connected by a passage 57 through piping 58, an intermediate section 59 of flexible hose and piping 60, with the bore of one of the tubular shafts 31; such connection, however, being controlled by a poppet valve 61 which is normally spring actuated to close such connection.

For the purpose of alternately unseating valves 61 at the proper time in the course of oscillation of the work carrier, the valve mechanism 50 includes a rocker 62 mounted to engage the stem of each of said valves, said rocker carrying a roller 63 disposed, when the corresponding valve with its stem is directed downwardly, to engage and rest on an abutment 64 which is, as a matter of convenience, attached to the pin 41 that carries the resilient stop 45. When one of the rollers thus engages abutment 64 the associated rocker is actuated to open the corresponding valve and thus permit the flow of lubricant, which will be supplied under suitable pressure to pipe 53, successively through passage 52 in shaft 5, the various passages included in the valve mechanism, and the system of piping and flexible hose which connects the latter with the work holder that at the time occupies the lowermost position in the carrier. This, it will be understood, is the position in which the mandrel rod and work-piece surrounding the same are aligned with the die for the drawing operation.

The section of flexible hose 59 interposed between pipe 58 and 60, and the connections between the valve mechanism and the respective work holders are for the purpose of accommodating such connections to the reciprocating movement of the holders. As best shown in Fig. 19, each such length of flexible hose is looped or doubled upon itself, and the outer portion of the loop (see Fig. 8) is received and guided in an inwardly facing channel member 65, one such member lying on each side and extending longitudinally of the reciprocable head that supports the work holders in the carrier. As a result of the construction just described, when a work holder is reciprocated the flexible hose section 59 folds or unfolds, as the case may be, along the corresponding channel guide in which it is thus received. In this way we do away entirely with the nuisance and danger of dangling lengths of hose for conducting the lubricant to the moving parts of the machine.

The point to which, of course, the lubricant requires to be ultimately supplied is the mandrel head or bulb 70 which is attached to the free end of the mandrel rod 71, i. e. the end directed towards the drawing mechanism proper. A typical construction of such mandrel head is shown in Fig. 19 (see also Fig. 20) where the upper man-

drel head with the rod to which it is attached appears in elevation in its retracted position while the lower such rod and head appear in section in their advanced position, i. e. in the position in which the head is located in proper operative relation to die 72 through which the tube T is being drawn by means of a drawing device D which may be of any well known construction. Ordinarily such device consists of opposed gripper jaws mounted on a carriage which may be connected to an endless chain or like driving means capable of moving the carriage with the end of the tube gripped thereto as indicated by the direction arrow. In order that the adjacent end of tube T may be introduced into the die and project therebeyond into position to be gripped by the jaws in device D, such end t is reduced in diameter as also shown in Fig. 20.

Referring further to the construction of the mandrel rod and head, such rod, it will be seen, is formed with a central passageway 73 extending its entire length, such passageway, when the rod is secured in holder 29 (see Fig. 9), constituting in effect a continuation of the passage 51 in the tubular work holder support 31. The head 70, which is secured as stated to the operative end of the mandrel rod, is formed with radial passages 74 which communicate with the central passageway 73 of the rod and permit the lubricant after traversing such last named passage to escape into the interior of the tube T immediately adjacent where the latter is being drawn through die 72. Excess lubricant beyond what may accumulate in the tube while thus being drawn may flow rearwardly and escape at the further end of the tube which abuts the work holder 29.

The upper tube T, as previously indicated, is shown in Fig. 20 in intermediate position in the course of its being loaded into the work carrier. Movement of the tube to the right over the mandrel head and rod may be effected in any way desired, but ordinarily mechanical means will be provided for the purpose, these means (only partly illustrated in the figure in question) include a vertically adjustable rest R and a pusher P actuated by an endless cable or the like which is disposed so as to engage the pinched end of a tube located on said rest and move the same to the right as indicated by the direction arrow. A stock of the tubes to be drawn may be carried on a rack or the like (not illustrated) adjacent such pusher's path of travel and one tube at a time may be drawn therefrom, placed in loading position and pushed into the carrier.

In its final loaded position the pinched end t of the tube will be brought in closely contiguous relation to the mandrel head 70 of the retracted mandrel rod 71. In this position such tube end will clear the die 72 and its mounting upon rotation of the work carrier.

To assist in supporting the tube as it is being loaded into the carrier and directing it through the successive guides 10 of the latter, a supplemental guide device is mounted on shaft 5 adjacent its right hand end as viewed in Figs. 1 and 2 and left hand end as viewed in Fig. 20. This device consists of two oppositely directed grooved rollers 75 which are normally pressed outwardly by springs 76 so that the upper thereof will engage with the tube being loaded in the manner just described. However, the lower tube which is being drawn through die 74 may drop so as partially to clear the other roller 75 and thus freely center itself in the die. A further support for the lower tube, i. e. the one thus being drawn, is pro-

vided in the form of a transverse roller 77 mounted on the bed of the machine, such roller being carried by swingable arms 78 (see Figs. 6 and 7) which may be held in desired position through an adjusting arm 79, in order to support the tube on a level with the die.

In addition to rollers 75 which serve to guide the work-piece into the carrier, the guide device illustrated in Figs. 4 and 5 is desirably provided to hold the free end of the mandrel rod in proper position to receive such work-piece, where the latter is of tubular form. This supplemental device, like the one previously described, is mounted on shaft 5 adjacent the loading end of the carrier, the supporting members 80 taking the form of flattened V's which are normally held by springs 81 in position to engage the mandrel rod in the same manner as the rollers 75 of the previously described device engage the work-piece. However, when the tube advancing over a mandrel strikes the corresponding support 80, the latter readily yields and drops out of the way. As best shown in Figs. 4, 5, and 20, spring 81 is part of a simple toggle operative to hold pivotally mounted support 80 out of contact with the tubing T once it has been thus displaced, thereby avoiding friction and possible jamming during the drawing operation. Handles 82 serve to return said supports again to operative position when required.

The operation of the several component parts or devices of our improved loading mechanism have been sufficiently described incidentally to a description of these parts. Accordingly, it remains only to set forth the general operation of the machine. The work-piece carrier, as already made clear, is designed to be rotated first in one direction and then the other through approximately 180° whereby first the one and then the other of the work holders 29, with its attached mandrel rod, is brought into the loading position illustrated in the upper part of Fig. 20. Simultaneously the second holder, with its mandrel rod, will be brought into alignment with the drawing mechanism proper, i. e. the die 72. The upper holder and mandrel rod during loading position will be retracted so that the tube received thereon may be rotated from the upper position illustrated in Fig. 20 to the lower position without interfering with any part of the mechanism. When the corresponding holder is brought into such lower position it is moved forwardly so as to bring the corresponding mandrel head into operative relation to the die and simultaneously the lubricant control valve is actuated to connect the lubricant passage in such holder and the mandrel rod carried thereby with the source of supply. As soon as the tube carried by such lower mandrel has been drawn entirely through the die, such mandrel is retracted and the carrier as a whole then oscillated in the opposite direction to its previous rotative movement and the several operations just described are repeated in the same order.

The movement of the several parts and devices of the machine may all be controlled from a single station which will be conveniently located adjacent the die where an operator will normally be required in order to watch the drawing operation. To this end the rods 35, which provide for the exact longitudinal adjustment of the mandrel heads in their relation to the die, extend to the corresponding end of the carrier where an operator thus stationed may effect such adjustment even during a drawing operation without leaving

his place. Since the work-piece carrier as a whole has only a rotative or rather oscillatory movement, it can be made of strong and substantial parts in counterdistinction to a carrier which requires to be bodily reciprocated in order to bring the work-pieces into and out of their loading and drawing positions. At the same time the several operative parts are simple and compact in their construction and not likely to get out of order. By having the guides 10 disposed towards the open sides of the C-shaped bearing rings whereby the shaft 5 of the carrier is supported and making such guides openable, the replacement or exchange of mandrel rods in order to adapt the carrier for the handling of different sizes of tubes may be readily effected. In other words, it is not necessary to introduce the rod longitudinally of the machine but it can be placed laterally into position for attachment to the work holder.

As previously indicated, our improved loading mechanism may be employed for drawing solid as well as tubular work-pieces. In that event mandrels will not be employed and the rods with their heads will accordingly be omitted. The work-pieces, however, will be successively introduced into the carrier in the same manner as above described and brought into position to be drawn. The described lubricating mechanism will in such case of course be disconnected since only exterior lubrication of the piece being drawn through the die will be necessary.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In loading mechanism for draw-benches and the like, the combination of a rotatably supported carrier, two longitudinally reciprocable work-piece holders in said carrier disposed in parallel, approximately diametrically opposed relation about the axis thereof, means adapted to oscillate said carrier to bring said holders alternately in alignment with the draw-bench, a member reciprocable longitudinally of the axis of said carrier and provided with a transverse slot, and an arcuate rib projecting radially from each of said holders adapted to engage with such slot as the holder is brought into alignment with the die.

2. In loading mechanism for a draw-bench including a die and a device for drawing a tube through such die, the combination of a rotatably supported carrier, longitudinally reciprocable holders in said carrier disposed in parallel, circumferentially spaced relation about the axis thereof, a mandrel attached at one end to each of said holders, means adapted to rotate said carrier to bring said mandrels successively in alignment with the die of said draw-bench, means adapted to supply lubricant through said holders, respectively, to the interior of a tube surrounding the mandrel attached to a holder, and means operating in unison with said carrier for controlling such lubricant supply.

3. In a loading mechanism for a draw-bench including a die and a device for drawing a tube through such die, the combination of a rotatably supported carrier, longitudinally reciprocable holders in said carrier disposed in parallel, circumferentially spaced relation about the axis thereof, a mandrel attached at one end to each

of said holders, means adapted to rotate said carrier to bring said mandrels successively in alignment with the die of said draw-bench, means adapted to supply lubricant through said holders, respectively, to the interior of a tube surrounding the mandrel attached to a holder, and control means limiting such supply to the tube on a mandrel in alignment with said die.

4. In a loading mechanism for a draw-bench including a die and a device for drawing a tube through such die, the combination of a rotatably supported carrier, longitudinally reciprocable holders in said carrier disposed in parallel, circumferentially spaced relation about the axis thereof, a mandrel attached at one end to each of said holders, means adapted to rotate said carrier to bring said mandrels successively in alignment with the die of said draw-bench, means adapted to supply lubricant through said holders, respectively, to the interior of a tube surrounding the mandrel attached to a holder, and control means limiting such supply to the tube on a mandrel in alignment with said die, said means including a valve operating synchronously with said carrier.

5. In a loading mechanism for a draw-bench including a die and a device for drawing a tube through such die, the combination of a rotatably supported carrier, longitudinally reciprocable holders in said carrier disposed in parallel, circumferentially spaced relation about the axis thereof, a mandrel attached at one end to each of said holders, means adapted to rotate said carrier to bring said mandrels successively in alignment with the die of said draw-bench, means adapted to supply lubricant through said holders, respectively, to the interior of a tube surrounding the mandrel attached to a holder, control means limiting such supply to the tube on a mandrel in alignment with said die, said means including a valve operating synchronously with said carrier, and flexible ducts leading from said valve to said holders, respectively.

6. In a loading mechanism for a draw-bench including a die and a device for drawing a tube through such die, the combination of a rotatably supported carrier, longitudinally reciprocable holders in said carrier disposed in parallel, circumferentially spaced relation about the axis thereof, a mandrel attached at one end to each of said holders, means adapted to rotate said carrier to bring said mandrels successively in alignment with the die of said draw-bench, means adapted to supply lubricant through said holders, respectively, to the interior of a tube surrounding the mandrel attached to a holder, control means limiting such supply to the tube on a mandrel in alignment with said die, said means including a valve operating synchronously with said carrier, flexible ducts leading from said valve to said holders, respectively, said ducts being doubled back in the direction of movement of said holders, and a guide disposed to receive and support each duct as it is undoubled incidentally to such movement.

7. A work-piece carrier for loading a draw-bench or like machine, comprising in combination a longitudinally extending shaft, longitudinally aligned work-piece guides mounted in opposite, radially projecting relation on said shaft, open-sided arcuate rings concentrically mounted on said shaft, the openings in said rings facing in the same direction and said guides lying within the space defined by said rings, and trunnion bearings for said rings.

8. A work-piece carrier for loading a draw-bench or like machine, comprising in combination a longitudinally extending shaft, longitudinally aligned work-piece guides mounted in opposite, radially projecting relation on said shaft, open-sided arcuate rings concentrically mounted on said shaft, the openings in said rings facing in the same direction and said guides lying within the space defined by said rings and being openable on the side corresponding with the openings in said rings, and trunnion bearings for said rings.

9. A work-piece carrier for a draw-bench or like machine, comprising in combination a longitudinally extending rotatable shaft, longitudinally aligned work-piece guides mounted in opposite, radially projecting relation on said shaft, a mandrel rod extending through said guides, supplemental, resiliently supported guides adapted to engage and support the work-piece, and independent means adapted to support said mandrel in position to receive a work-piece.

10. A work-piece carrier for a draw-bench or like machine, comprising in combination a longitudinally extending rotatable shaft, longitudinally aligned work-piece guides mounted in opposite radially projecting relation on said shaft, a mandrel rod extending through said guides, supplemental, resiliently supported guides adapted to engage and support the work-piece, and independent, displaceable means adapted to support said mandrel in position to receive a work-piece.

11. In loading mechanism for draw benches and the like the combination of a rotatably supported carrier, two longitudinally reciprocable workpiece holders in such carrier disposed in parallel approximately diametrically opposed relation about the axis thereof, means adapted to oscillate said carrier to bring said holders alternately in alignment with the draw bench, and a single means operative positively to reciprocate said respective holders comprising a member reciprocable parallel to the axis of said carrier and means on said member adapted lockingly to engage with the respective holder thus aligned.

12. In loading mechanism for draw benches and the like the combination of a rotatably supported carrier, two longitudinally reciprocable workpiece holders in said carrier disposed in parallel approximately diametrically opposed relation about the axis thereof, means adapted to oscillate said carrier to bring said holders alternately in alignment with the draw bench, and a single means operative thus positively to reciprocate said respective holders comprising a member

reciprocable parallel to the axis of said carrier and provided with a transverse engaging element, and a complementary element on each of said holders adapted alternately lockingly to engage with said element on said member as such holder is brought into alignment with the die of such draw bench.

13. A workpiece carrier for a draw bench or like machine comprising in combination longitudinally aligned work-piece guides for guiding a tubular work-piece to the die of such draw bench, a mandrel rod extending through said guides and adapted to have such tubular work-piece received thereon, a temporary support for said mandrel rod pivotally mounted intermediate the ends of the latter and adapted to be engaged and displaced by a tubular work-piece in course of being received on said mandrel rod, and toggle means adapted to hold said pivotally mounted support out of engagement with such tubular work-piece when thus displaced.

14. A workpiece carrier for a draw bench or like machine comprising in combination longitudinally aligned work-piece guides for guiding a tubular work-piece to the die of such draw bench, a mandrel rod extending through said guides and adapted to have such tubular work-piece received thereon, a temporary support for said mandrel rod pivotally mounted intermediate the ends of the latter and adapted to be engaged and displaced by a tubular work-piece in course of being received on said mandrel rod, and means adapted to hold said pivotally mounted support out of engagement with such tubular work-piece when thus displaced.
